UNITED STATES PATENT OFFICE.

LE ROY J. CHAPMAN, OF SALT LAKE CITY, UTAH.

STAPLE-WIRE CLINCHER.

Application filed March 22, 1924. Serial No. 701,124.

To all whom it may concern:

Be it known that I, LE ROY J. CHAPMAN, a citizen of the United States, residing at Salt Lake City, in the county of Salt Lake and State of Utah, have invented a new and useful Staple-Wire Clincher, of which the following is a specification.

This invention aims to provide novel means for holding a fence wire on a fence post.

It is within the scope of the disclosure to improve generally and to enhance the utility of devices of that type to which the invention appertains.

With the above and other objects in view, the invention consists in the novel construction and arrangement of parts hereinafter described, claimed and shown in the drawings, it being understood that a mechanic, working within the scope of what is claimed may make such changes as his skill may dictate, without departing from the spirit of the invention.

In the drawings:—

Figure 1 shows in perspective a device constructed in accordance with the invention; Figure 2 is a top plan showing the device applied, parts being broken away; Figure 3 is an elevation showing a modification.

The device forming the subject matter of this application is made of metal and includes a prong 1, which is pointed as shown at 2, and is stiff enough so that it can be driven into a post. An arm 3 is joined to the prong 1 and is flexible enough so that it may be wound about a fence wire. The prong 1 is disposed at an acute angle to the arm 3 at the point of juncture between the prong and the arm, and it may receive a hammer blow to advantage the end in view being that the prong

2 may be driven into a post 7, the arm 3 being wrapped as indicated at 8 about a fence wire 9 to hold the wire against the post 7. For the sake of strength, the prong and the arm 3 may be joined by an enlargement 5, which is flattened as at 6, so as to receive a hammer blow conveniently.

In the modification shown in the Figure 50 3, parts hereinafter described have been designated by numerals previously used with the suffix "a". The modification consists in omitting the enlargement 5 and the flattened surface 6. 55

Having thus described the invention, what is claimed is:—

1. In a device of the class described, a prong and an arm joined to produce an angle which is sufficiently prominent to receive a hammer blow, the prong being stiff enough so that it can be driven into a post, and the arm being flexible enough so that it can be wrapped about a fence wire, there being an enlargement, for the reception of a hammer blow, at the point of juncture between the prong and the arm. 65

2. In a device of the class described, a prong and an arm joined to produce an angle which is sufficiently prominent to receive 70 a hammer blow, the prong being stiff enough so that it can be driven into a post, and the arm being flexible enough so that it can be wrapped about a fence wire, the prong and the arm being joined by an enlargement having a flattened surface adapted 75 for the reception of a hammer blow.

In testimony that I claim the foregoing as my own, I have hereto affixed my signature in the presence of two witnesses.

LE ROY J. CHAPMAN.
